Primary Examiner — Mary Ann Calabrese

Assistant Examiner — Mark David Wolfley

(74) Attorney, Agent, or Firm — Sheridan Ross P.C.

(57) **CLAIM**

The ornamental design for a task chair as shown and described.

DESCRIPTION

FIG. 1 is a top front perspective view of a task chair;
FIG. 2 is a bottom rear perspective view thereof;
FIG. 3 is a front elevation view thereof;
FIG. 4 is a rear elevation view thereof;
FIG. 5 is a right side elevation view thereof;
FIG. 6 is a left side elevation view thereof;
FIG. 7 is a top plan view thereof;
FIG. 8 is a bottom plan view thereof; and,
FIG. 9 is a bottom plan view thereof, with the base removed
for clarity.

The broken lines in the drawings illustrate portions of the
task chair, which form no part of the claimed design.

1 Claim, 9 Drawing Sheets
